SLIDER FOR SLIDE FASTENERS

Gideon Sundback, Meadville, Pa., assignor to
Talon, Inc., Meadville Pa., a corporation of
Pennsylvania

Application July 19, 1939, Serial No. 285,363

10 Claims. (Cl. 24—205.5)

This invention relates to slide fasteners and, in particular, to the provision of sliders therefor.

It is an object of this invention to provide an improved slider for slide fasteners which is of the automatic or self-locking type and which is positive in operation, strong, durable, compact, and economical to manufacture because of its simplicity of construction and the ease with which the parts thereof may be assembled.

It is a further object of this invention to provide such a slider construction wherein the biasing means, adapted normally to urge the locking means thereof into engagement with slide fastener elements, comprises an elongated spring member of the leaf, or substantially flat, type.

It is a further object of this invention to provide such a construction wherein the biasing spring means is of substantial length and wherein, in addition to its function in normally resiliently biasing the locking means to locking position, it also provides yielding connection between the locking lug of the slider and the body thereof.

It is a further object of this invention to provide such a construction wherein the biasing spring means, in addition to performing the above enumerated functions, also operates as yielding stop means for limiting movement of the locking lug of the slider inwardly with respect to the body.

It is a further object of this invention to provide such a construction wherein the biasing spring means operates as yielding stop means for limiting movement of the locking lug both inwardly and outwardly with respect to the slider body.

It is a further object of this invention to provide a slider construction of the utmost simplicity and wherein the biasing spring means projects from the lower end of the slider upwardly throughout a substantial proportion of the length thereof.

These and other objects and advantages of the invention will appear from the following description taken in conjunction with the accompanying drawing which forms a part thereof, and will be pointed out in the appended claims.

In the drawing:

Fig. 1 is a plan view of the lower portion of a slide fastener embodying my slider construction as a component part;

Fig. 2 is an enlarged longitudinal section taken substantially on the line 2—2 of Fig. 1, the slider parts being shown in locking position;

Fig. 3 is a view similar to Fig. 2 but showing the slider parts in unlocking position;

Fig. 4 is a transverse section taken substantially on the line 4—4 of Fig. 2;

Fig. 5 is a longitudinal section in perspective of the slider construction illustrated in Figs. 1 to 4 inclusive, certain parts thereof being shown in section in the interest of clearness of disclosure;

Fig. 6 is an enlarged longitudinal section, similar to Fig. 2, of a modified slider construction according to the principles of this invention; and

Fig. 7 is a view similar to Fig. 5 of the modified form of slider construction illustrated in Fig. 6.

Referring to the drawing in detail, and with reference particularly to Fig. 1 wherein, for the purposes of illustration only, I have shown the application of my improved slider to an otherwise conventional slide fastener of the non-separating type, the slide fastener stringers are generally designated 10 and are secured together at their lower ends by suitable bottom stop means, generally designated 11. The stringers 10 each comprise a tape or strip 12 of suitable material to which are secured, in suitable relationship, the fastener members 14 which are adapted for interengagement in known manner to secure the adjacent edges of the stringers 10 together.

The engagement and disengagement of the fastener members 14 is accomplished by longitudinal movement of the slider, generally designated 15, longitudinally with respect to the stringers 10. A bifurcated pull member 16 with a manually engageable pull tab 18 is provided for this purpose.

The details of the slider 15 of Fig. 1 are illustrated in Figs. 2, 3, 4 and 5 wherein it will be seen that the body thereof is of solid, cast or molded construction. The body comprises the rear or back wing 19 and the front wing 20, which are secured together in parallel spaced relationship by means of the wedge or wedge-forming web 21 disposed between their upper ends and integral therewith. The wedge or web 21 is provided with inclined exterior surfaces disposed between the back and front wings which define a downwardly directed V and which cooperate with the marginal side flanges 23 on the back wing 19 and the marginal side flanges 24 on the front wing 20 to form an upwardly diverging substantially Y-shaped channel 25 in which the fastener elements 14 of the stringers 10 are guided in known manner, as shown in Figs. 2, 3 and 4.

While the back wing 19 is of solid construc-

tion, as shown, the front wing 20 is provided with a centrally disposed longitudinal slot 27 extending from the outer surface thereof into the channel 25. The side walls of this slot are designated 5 28 and are flat, and at each side of the slot 27 is a longitudinal recess 29 (Fig. 1), which is adapted slidably to receive one furcation 16a of the pull 16, as indicated in the drawing. Dis- posed between these recesses 29 at the lower end 10 of the wing 20 is a lug 30 which cooperates with the recesses 29 to guide the furcations 16a of the pull 16. The upper end wall of the slot 27 is doubly inclined to form the transverse projection 31 of substantially triangular section, which 15 projection cooperates with notch means on the locking lug to form a hinge connection, as hereinafter most clearly described.

The lower end wall 32 of the slot 27 is flat and slightly inclined, as shown in Figs. 2 and 3. 20 Disposed in the slot 27 is the locking lug 33 which is provided with a transverse slot 34 adapted slidably to receive the pivot projections 17 extending inwardly toward one another from the furcations 16a of the pull 16.

25 The upper end wall of the locking lug 33 is provided with a notch 35 adapted to cooperate with the above described projection 31 to form a hinge connection between the locking lug 33 and the slider body, as shown in Figs. 2 and 3. 30 The lower end wall of the locking lug 33 is inclined and is substantially parallel with the lower end wall 32 of the slot 27 when the locking lug is in locking position, as shown in Fig. 2. Ex- 35 tends inwardly from one side of the lower end portion of the locking lug 33 is a locking pro- jection of pin 36 which is adapted, in the locking position of the locking lug 33, to project into the channel 25 for engagement with fastener mem- bers 14, as shown in Fig. 2. The relationship 40 between the length of the slot 27 and the length of the locking lug 33 is such that the locking projection or pin 36 cooperates with the lower end wall 32 of the slot 27 to limit pivotal move- 45 ment outwardly of the locking lug 33 with respect to the slider body, as shown in Fig. 3.

Extending from the lower end of the inner wall of the locking lug 33 is a recess or channel 37 which extends to a point beyond the middle of the locking lug 33 and which terminates in 50 a transverse notch 38 which is slightly inclined upwardly. Received by this channel 37 with its upper end disposed in the notch 38 is a substan- tially L-shaped leaf spring member 39 which has the short leg 40 thereof disposed at substan- 55 tially ninety degrees to the long leg thereof and secured in notches 41 provided in the above de- scribed lug 30.

The spring 39, hereinafter termed the biasing spring, normally urges the locking lug 33 inwardly of the slider body to the locking position illustrated in Fig. 2. The slider may be unlocked from the stringers 10 by manual engagement of the pull tab 18 of the pull 16 to pull the locking lug 33 outwardly against the force 60 of the biasing spring 39 to the position shown in Fig. 3. In that position, the locking pin or projection 36 is disposed outside the channel 25, and the stringers and their fastener mem- bers 14 may slide freely with respect to the 65 channel 25, or vice versa, when the parts are in this position. Upon release of the pull 16, the parts will return to the position of Fig. 2, where- 70 upon the slider 15 will be locked with respect to the stringers 10. While only one locking pin or projection 36 is illustrated, it is, of course,

75 to be understood that a plurality of these pro- jections may be provided for engaging the fas- tener members 14 of the stringers 10.

It is likewise to be understood that the slider body and the locking lug may be formed of mold- 5 ed plastic material or of cast metallic material. In either case, the biasing spring member 39 will, of course, be formed of suitable resilient 10 spring metal.

If the slider body is formed of metal, then 10 the notches 41 are formed subsequent to the for- mation of a substantially rectangular slot in the wing 20, whereafter the lower or short leg 40 of the biasing spring 39 is positioned in the slot, and the corners of the slot are upset or beaded 15 over upon the leg 40 to secure it rigidly with respect to the wing 20.

If the slider body is formed of plastic mate- 20 rial, then the notches 41 are formed subsequent to the formation of a rectangular slot in the wing 20 by the application of suitable solvent to the corner portions of the slot, which is followed by application of pressure rigidly to secure the leg portion 40 of the spring 39 with respect to the 25 lug 30.

In order to assemble the slider illustrated in 30 Figs. 1 to 5, the locking lug 33 is inserted through the lower end of the channel 25 and then pushed outwardly substantially to the position shown in Fig. 2. The pivot projections 17 of the pull 34 35 are snapped into the pull supporting slot 34 in the locking lug 33. The upper end of the long leg of the biasing spring 39 is inserted in the notch 38 in the locking lug 33, and the short leg portion 40 of the biasing spring 39 is se- 40 cured to the lug 30 of the slider body by the formation of the notches 41 by the above de- scribed procedure. The slider is then assembled 45 and ready for use in slide fasteners of various known types and constructions.

In the modification illustrated in Figs. 6 and 50 7, the details of the pull 16 are unchanged. The slider body, designated 15a is, however, somewhat modified. The back wing 19a of the slider body 15a and also the wedge or wedge-forming web 21a are similar to corresponding parts of the 55 slider body 15, illustrated in Figs. 1 to 5. The front wing 20a, however, is somewhat modified. This front wing 20a is provided with marginal side flanges 24a, corresponding with marginal side flanges 24 of the above described front wing 20. These marginal side flanges 24a cooperate with marginal flanges 23a of the back wing 19a, corresponding with the above described marginal side flanges 23, and with the wedge or wedge- 60 forming web 21a to form between the wings 19a and 20a a channel 25a, corresponding with the above described channel 25.

The front wing 20a is provided with a slot 27a, having flat side walls 28a, flat inclined lower 65 end wall 32a, and upper end wall forming a pro- jection 31a, all corresponding with analogous parts of the construction of Figs. 1 to 5. At each side of the slot 27a are recesses 29a, cor- 70 responding to recesses 29, of the construction 65 of Figs. 1 to 5.

The lug 30a, which corresponds to the lug 30, is somewhat modified, being provided with a longitudinal bore 41a instead of the notches 41. The bore 41a is substantially cylindrical but pro- 75 vided at opposite sides with grooves adapted to receive keys or feathers provided on the lower or outer, thickened, substantially cylindrical end 40a of the modified biasing spring 39a. The in- 80 ner end portion of the biasing spring 39a which 75

extends beyond the lug 30a is flattened, as shown in Figs. 6 and 7. This biasing spring 39a is substantially flat or straight, and like the biasing spring 39, is of substantial extent, extending substantially to the upper end of the modified locking lug 33a.

The modified locking lug 33a, corresponding to the locking lug 33 of the construction of Figs. 1 to 5, is provided at its upper end with a notch 35a, corresponding to the above described notch 35 and cooperating with the projection 31a formed by the upper end wall of the slot 21a to provide a hinged or pivotal connection between the locking lug 33a and the slider body. At its lower end, the locking lug 33a is provided with a locking projection of pin 36a, corresponding to the locking pin 36. The lower end portion of the locking lug 33a differs from the corresponding portion of the above described locking lug 33 only in the omission of the channel 37 and notch 38 and in the provision of an aperture 43a through which the biasing spring 39a is adapted to project, as shown in Figs. 5 and 6. This aperture 43a communicates with a channel 44a, which is in the form of a recess extending downwardly from the lower inner surface of the pull supporting slot 34a, which corresponds to the slot 34 in the above described locking lug 33. This channel or recess 44a is curved, as shown in Fig. 6. This curvature and the length of the aperture 43a makes the functioning of the biasing spring 39a, in cooperation with the aperture 43a, as a resilient stop means for limiting the pivotal movement of the locking lug 33a with respect to the body 30 of the slider, both inwardly (Fig. 6) and outwardly (Fig. 7) to locking and unlocking positions respectively.

The slider assembly illustrated in Figs. 6 and 7 may be assembled with extreme ease and convenience. In order to assemble the pull, locking lug, and biasing spring to the slider body, it is merely necessary to insert the locking lug through the lower end of the channel 25a in the slider body to position below the slot 21a, thrust the locking lug 33a outwardly to the position of Fig. 6, snap the pivot projections 17 of the pull 16 into the slot 34a, and then insert the biasing spring 39a endwise through the bore 41a in the lug 30a to the position of Fig. 6. If the parts are formed of plastic, the frictional attachment of the spring 39a may be accompanied by a bonding achieved by the application of solvent either to the interior of the bore 41a before insertion of the spring end portion 40a or by application of solvent directly to the end portion 40a of the spring before its insertion in the bore.

If the slider body be formed of metal, then the frictional attachment may be emphasized by upsetting the metal adjacent the outer end of the bore 41a.

From the above description, it will be seen that the constructions herein illustrated and described embody various advantages over known prior art structures, which include the use of a long biasing spring, compactness, and extreme ease and convenience of assemblage, which latter feature materially decreases the cost of manufacture.

It is, of course, to be understood that the above described structure is merely illustrative and in no wise limiting and that I desire to comprehend within my invention all modifications included within the scope of the appended claims.

Having thus fully described my invention, what I claim as new and desire to secure by Letters Patent is:

1. In a slider for slide fasteners, a slider body having a fastener member receiving channel therein and having a longitudinal locking lug receiving slot in one side thereof communicating with said channel, a locking lug in said slot having pivotal connection with said body at one end of said slot, said locking lug having thereon locking pin means engageable with fastener members in said channel in the locking position of said locking lug, and a flat leaf spring disposed substantially longitudinally of said body and having one end thereof rigidly secured to said body adjacent the opposite end of said slot, said leaf spring having the other end thereof engaging said locking lug for normally resiliently urging said locking lug to locking position.

2. In a slider as defined in claim 1, said locking lug having herein a longitudinal slot, and a bifurcated pull member having pivotal projections slidably and pivotally supported in said longitudinal slot, said pull member being manually engageable for withdrawing said locking lug from locking position, against the yielding force of said leaf spring.

3. In a slider as defined in claim 1, said locking lug having therein a longitudinal slot, and a bifurcated pull member having pivotal projections slidably and pivotally supported in said longitudinal slot, said pull member being manually engageable for withdrawing said locking lug from locking position, against the yielding force of said leaf spring, and said slider body having recesses at opposite sides of said locking lug receiving slot for recessing said pull member in said slider body in the flat position of said pull member and cooperating with said pull member positively to limit inward movement of said locking lug to locking position.

4. In a slider for slide fasteners, a slider body having a fastener member receiving channel therein and having a longitudinal locking lug receiving slot in one side thereof communicating with said channel, said locking lug receiving slot having the upper end thereof doubly inclined to form a projection, a locking lug in said slot having the upper end thereof provided with a notch complementary with the projection in the end of said locking lug receiving slot, said locking lug having locking pin means at the lower end thereof engageable with fastener members in said channel in the locking position of said locking lug, and a flat leaf spring having the lower end thereof secured rigidly to said body adjacent the lower end of said locking lug receiving slot and having the upper end thereof engaging said locking lug for normally yieldingly urging said locking lug to locking position and forming yieldable stop means for delimiting the locking position of said locking lug.

5. In a slider for slide fasteners, a slider body having a fastener member receiving channel therein and having a longitudinal locking lug receiving slot in one side thereof communicating with said channel, said locking lug receiving slot having the upper end thereof doubly inclined to form a projection, a locking lug in said slot having the upper end thereof provided with a notch complementary with the projection in the end of said locking lug receiving slot, said locking lug having locking pin means at the lower end thereof engageable with fastener members in said channel in the locking position of said locking lug, and a flat leaf spring having the lower end thereof secured rigidly to said body adjacent the lower end of said locking lug receiving slot and

- 5 having the upper end thereof engaging said locking lug for normally yieldingly urging said locking lug to locking position and forming yieldable stop means for delimiting the locking position of said locking lug, said leaf spring cooperating with said locking lug yieldably to limit outward movement of said locking lug to define the unlocked position thereof.
6. In a slider for slide fasteners of the class described, a slider body having a slide fastener member receiving channel therein, and a longitudinal locking lug receiving slot extending from one side of said body to said channel, a locking lug in such slot having hinged connection with 10 said body at one end of said slot, said locking lug having therein a notch open toward the opposite end of said slot, and a leaf spring member rigidly secured to said body at one end and having the opposite end thereof disposed in said 15 notch.
7. In a slider for slide fasteners of the class described, a slider body having a slide fastener member receiving channel therein and a longitudinal locking lug receiving slot extending from 20 one side of said body to said channel, a locking lug in said slot having hinged connection with said body at the upper end of said slot, said locking lug having therein a longitudinal pull receiving slot with an aperture at the lower end 25 thereof, and a leaf spring member having one end rigidly secured to said body adjacent the lower end of said locking lug receiving slot, said leaf spring member projecting through the aperture in said locking lug and having the upper 30 end thereof in engagement with a wall of said pull member receiving slot.
8. In a slider for slide fasteners of the class described, a slider body having a slide fastener member receiving channel therein and a longitudinal locking lug receiving slot extending from 35 one side of said body to said channel, a locking lug in said slot having hinged connection with said body at the upper end of said slot, said locking lug having therein a longitudinal pull receiving slot with an aperture at the lower end 40
- 5 thereof, and a leaf spring member having one end rigidly secured to said body adjacent the lower end of said locking lug receiving slot, said leaf spring member projecting through the aperture in said locking lug and having the upper 45 end thereof in engagement with a wall of said pull member receiving slot.
9. In a slider for slide fasteners of the class described, a slider body having a fastener member receiving channel therein and having a longitudinal locking lug receiving slot in one side 15 thereof communicating with said channel, said locking lug receiving slot having a projection formed in one end thereof, a locking lug in said slot having a notch at one end engageable with said projection for providing interlocking pivotal 20 connection between said locking lug and said body, and leaf spring means rigidly secured to said slider body at the opposite end of said locking lug receiving slot and cooperating with said locking lug to maintain said notch in engagement with said projection while normally yieldingly urging said locking lug to locking position and limiting movement thereof toward locking 25 position.
10. In a slider for slide fasteners of the class 30 described, a slider body having a slide fastener member receiving channel therein and a locking lug receiving slot disposed longitudinally with respect to said slider body and extending from one side of said body into said channel, a locking lug of substantially the same length as said slot supported movably in said slot for engagement with said fastener members in said channel and for disengagement therefrom, and a spring member having one end fixed to said body 35 and having the free end thereof engaging said locking lug for normally biasing said lug toward engagement with slide fastener members in said slide fastener member receiving channel.

GIDEON SUNDBACK. 45
